SANDER, SAND SPRAY, OR DISTRIBUTOR

Frank S. Blakesley, Chicago, Ill.

Application July 21, 1936, Serial No. 91,770

Renewed March 3, 1938

1 Claim. (Cl. 275—14)

This invention relates to a sander, sand spray or distributor generally. It is particularly aimed to provide a novel means to supplant the present hand method of distributing sand, ashes, cinders, fine stone, or the like over icy pavements in order to minimize the danger of slippage of pedestrians. The invention however is capable of use as a distributor generally however as for seed, fertilizer and various other materials.

10 A particular object is to provide a novel means for distributing the sand or equivalent so that the sand will bound from the apparatus in a lively spray, depositing in an even layer upon the ground.

15 The more specific objects and advantages will become apparent from a consideration of the description following taken in connection with accompanying drawings illustrating an operative embodiment.

20 In said drawings:—

Figure 1 is a view in side elevation of the apparatus;

Figure 2 is a plan view thereof;

Figure 3 is an enlarged detail sectional view taken on the line 3—3 of Figure 2;

Figure 4 is an end elevation of the apparatus;

Figure 5 is a detail section taken on the plane of line 5—5 of Figure 3; and

30 Figures 6 and 7, detail the clutches and pin connections between the axle and wheels, being taken on the line 6—6 and 7—7, respectively, of Figure 5.

Referring specifically to the drawings wherein like reference characters designate like or similar parts, a suitable frame is provided as at 10, preferably endless and made of metallic pipe or tubing, or otherwise, having horizontal portions 11, a raised handle bar section or portion at 12 and a lowered forward portion 13 on which a pair 40 of small wheels 14 are journalled, being held in position between couplings 15 and pins or pegs 16.

Bolted as at 17 to the side portions 11 are side plates 18 which are also bolted as at 19 to a hopper or container 20, preferably having its front 45 and rear walls downwardly and inwardly inclined as shown in Figure 3, the hopper normally being closed by a cover 21 hinged or pivoted to the hopper as at 22. Said hopper 20 is adapted to contain the sand, crushed rock, cinders or other 50 material to be distributed.

The lower portions of the plates 18 extend below the hopper 20 and are in the form of bearings 23. A main or distributor shaft is shown 55 at 24, disposed beneath the hopper and having axle portions 25 at opposite ends thereof and of

reduced diameter. A pair of large ground wheels 26 are mounted on the axle portions 25, secured against displacement by cotters 27 or the like. The hubs 28 of the wheels 26 have cut-out portions 29 about the axle portions 25, provided with arcuate walls at 30. Coacting with these cut-out portions 29 are pins 31, which are slidable in openings 32 arranged diametrically of the shaft portions 25. The cut-away portions 29 and pins 31 constitute clutches that cause the 10 shaft 24 to turn unitarily with the wheels 26 as the device moves forwardly but permits the wheels to slip past the pins on backing or reverse movement of the wheels, so that the shaft 24 will not turn therewith.

Attention is called to the fact that the tread or periphery of the wheels 26 is dished to provide relatively close projecting portions 33, or such periphery may be otherwise roughened or irregular so that the machine will constantly jar as it is pushed along, aiding in the agitation and discharge of the sand or the equivalent.

Braces 34 are connected at opposite ends to the frame 10 and at 35 to the sides of the hopper.

The bottom wall of the hopper is shown at 36, 25 having a row of equidistantly spaced discharge openings therethrough adapted to register with discharge wells or depressions 38 in the periphery of the shaft 24. And an intermediate bar 39 is provided having openings 40 therethrough registering with the openings 37. A plate 41 integral with or otherwise secured to the bar 39 extends downwardly and forwardly therefrom, being equipped with braces at 42 bolted or otherwise fastened as at 43 to the portions 11 of frame 10. 30 In the line of discharge of the sand or the like, that is in line with the wells 38, raised portions 44 are provided on the plate 41.

Attention is called to the fact that the openings 37 are in rows in which the wells 38 of successive rows register with alternate openings 37, to avoid too rapid a discharge of the sand and assist in obtaining the desired spray, it being clear that the sand or other particles discharged by the wells engage and bind on the elements 44, assisting in producing the desired spray forming an even layer over the ice or the like. It will be noted that said member 44 are of ovolo shape. Since the sand or other material is of such density as to rebound when striking a hard or 45 solid object, such rebound assists in producing the spray, when the sand or the equivalent engages the striker members 44.

The discharge of the sand or the equivalent is under control of a damper or valve plate 45 slid-

able over the bottom of the hopper, guided by brackets 46 bolted or otherwise secured at 19 to the hopper. Said valve plate 45 has openings 48 therein adapted to register with the openings 37.

Such plate has a bracket 49 fastened thereto to which a resilient latch arm 50 is fastened at 51, such latch arm passing through an enlarged opening 52 in a guide block 53 to which the latch arm is pivoted as at 54. Such latch arm is adapted for engagement in suitable notches 55 of a bracket 56, to hold the valve plate 45 in position aligning the openings 48 and 37 or closing the latter openings. It will be realized that the plate 53 and bracket 56 are suitably secured to one side of the hopper 20. An operating handle 57 is preferably provided on the latch rod 50.

It is clear that the device may be made of any desired material and in any desired size. Since the present embodiment merely shows operation by hand, no limitation is to be implied since forms may be resorted to in which operation is effected by any suitable power. Other changes may be made within the spirit and scope of the invention.

In the operation of the device, it is pushed along with the wheels 14 elevated from the ground, the wheels 26, jarring the entire device, due to the projections 33, and the sand or other material discharges through the aligned openings

48, 37, wells 38 and onto the striker blocks 44, bounding therefrom in a spray and depositing evenly upon the ice or surface being sanded. When it is desired to cease sanding, the latch rod 50 is operated to dispose imperforate portions of 5 the valve 45 over the openings 37. When adjacent a curb or other obstruction, the handle bar 12 may be depressed so as to place the wheels 14 beyond the curb or upon the higher plane, and the remainder of the device lifted as an aid in moving over the curb or obstruction.

Various changes may otherwise be made.

I claim as my invention:—

An apparatus of the class described comprising a frame, plates on said frame provided with bearings at their lower ends, a distributing shaft between the plates having axle portions journaled in said bearings, a hopper fastened to the plates above said shaft, ground wheels engaged with said axle portions, means onto which sand or the like is dropped by the distributing shaft so as to rebound in a spray, said means comprising a forwardly inclined plate, said plate being spaced from and mounted directly underneath said distributing shaft, and striker elements on the last mentioned plate for engagement by the said sand or the like of substantially ovolo form.

FRANK S. BLAKESLEY.
